FOLDING CHAIR

Giancarlo De Carlo, Milan, Italy, assignor to J. G. Furniture Company, Inc., Quakertown, Pa.

Filed Feb. 1, 1971, Ser. No. 111,798

Term of patent 14 years

Int. Cl. D6—02

U.S. Cl. D6—41

FIG. 1 is a perspective view of a folding chair embodying my new design with the seat opened;

FIG. 2 is a front view of the opened folding chair of FIG. 1;

FIG. 3 is a top plan view of the opened folding chair of FIG. 1;

FIG. 4 is a back view of the folding chair of FIG. 1;

FIG. 5 is a side view of the opened folding chair of FIG. 1;

FIG. 6 is a side view of the folding chair of FIG. 1 with the seat closed; and

FIG. 7 is a top plan view of the closed folding chair of FIG. 6.

I claim:

The ornamental design for a folding chair, as shown and described.
